JOHN J. MURPHY, OF NORWICH, CONNECTICUT, ASSIGNOR, BY MESNE ASSIGNMENTS,
TO PEERLESS HANDCUFF COMPANY, A CORPORATION OF MASSACHUSETTS.

HANDCUFF.

Application filed February 24, 1924. Serial No. 690,068.

This invention relates to improvements in handcuffs.

The general type of handcuff, with which this invention is concerned, comprises a

5 body or frame, having a fixed arm, and a locking arm usually pivoted to the fixed arm and cooperating therewith to form an embrasure for the wrist. Suitable locking means are provided in the frame, usually in
10 the nature of a key retractable pawl which is spring pressed outwardly to engage with ratchet teeth on the locking arm. The locking means is so arranged as to permit the locking arm to be moved in one direction
15 into wrist embracing position and to permit continued movement in the same direction, so that the embrasure afforded by the two arms may be made as small as is necessary after the initial engagement of the locking
20 arm with the locking means. Reverse movement of the locking arm is, however, prevented except when the pawl is retracted by the key.

For convenience in carrying the handcuff, 25 the locking arm is ordinarily engaged with the locking means, when the handcuff is not in use, and it is desirable to provide means whereby the locking arm may be quickly released and moved to open position without resort to the key. One arrangement, 30 heretofore proposed for such purpose, is to make the locking arm completely revoluble so that after it has been moved in one direction into engagement with the locking
35 means, it may by continued movement in the same direction, be moved beyond and freed from the locking means and brought into open position. There are, however, many forms of handcuffs which are so constructed 40 that the locking arm cannot be completely revolved and this invention is concerned with a means for permitting disengagement of the locking arm from the locking means without resort to the key in a
45 different and improved manner and in a manner applicable alike to handcuffs, wherein in the locking arm cannot be completely revolved, and to handcuffs wherein such arm can be completely revolved.

50 The general object of the invention is to provide means whereby, after the locking arm has been moved in one direction into engagement with the locking means, it may by continued movement in the same direc-

tion, be moved to a position wherein it may 55 be freed from the locking means and subsequently moved in a reverse direction into open position.

The position of the locking arm, in which it is thus freed from the locking means, is 60 such that the embrasure afforded by the locking arm and the cooperating part of the frame is smaller than the wrist, so that the locking arm can only be released when the handcuff is not in place on the wrist. 65

More particularly, it is an object of the invention to provide means whereby when the arm is moved to a predetermined position, it may then be moved substantially 70 radially away from the pawl of the locking means and disengaged therefrom.

Another object of the invention is to provide, in a handcuff of the general class described, a locking arm pivoted to the frame of the handcuff through the intermediary of 75 a link which normally does not move relatively to the arm and is positively held from such movement while engaged with the locking means except at one position, in which the locking arm may be lifted by reason of 80 the link connection to free itself from the locking means.

Other objects and advantages, relating to 85 improvements in the construction and arrangement of parts, will appear in the following description and in the illustrative embodiment of the invention in the accompanying drawings, in which—

Fig. 1 is a front elevational view of a 90 handcuff embodying the invention, certain parts being broken away to reveal interior construction;

Fig. 2 is a side elevational view of the same;

Fig. 3 is a fragmentary sectional elevational view showing the manner in which the locking arm is pivotally connected to the frame; 95

Fig. 4 is a sectional plan view taken on the line 4—4 of Fig. 1;

Fig. 5 is a detail view of a part shown in Fig. 4; and

Fig. 6 is a fragmentary sectional view taken on the line 6—6 of Fig. 1.

Referring to these drawings, the handcuff, 105 as shown, includes a frame having a body portion 10 and curved arms 11 extending therefrom in approximately semi-circular

fashion to form part of the embrasure for the wrist. This embrasure is completed by a cooperating and similarly curved locking arm 12 which is pivoted to and between arms 11, near their free ends, at the point 13. The arms 11 are laterally spaced to permit free movement of the locking arm 12 therebetween but, in the form illustrated, these arms, near their outer ends have been merged together leaving a solid portion 14 therebetween which prevents complete rotation of the locking arm 12. In the particular form illustrated, the body 10, one arm 11, and the portion 14 are integral and the other arm 11 is riveted to the portion 14 as at 15, and has a lower portion 16, shaped to the contour of body portion 10, which is secured, as by rivets 17, to and forms a closure for the latter, as shown in Figs. 2, 4, and 6. This particular construction, however, is not at all essential and may be varied as desired.

In the body 10, any suitable locking means may be provided to cooperate with arm 12 and hold it in wrist embracing position. Usually such locking means includes a pawl 18, which is slidably mounted in a recess 19 in body 10 and resiliently urged upwardly by a spring 20 to cooperate with ratchet teeth 21 formed on arm 12. The pawl 18, as shown, is recessed intermediate its ends at 22 (Figs. 1 and 4) to receive a pawl depressor 23, which is pivotally mounted on a pin 24 fixed to body 10 and yieldingly urged upwardly by a spring 25. The latter normally holds depressor 23 in the illustrated position, wherein a shoulder 26 thereon abuts a side wall of recess 19 to limit upward movement of the depressor. The latter is adapted to move pawl 18 downwardly by its engagement with a shoulder 27 on the pawl, which, as shown, can also move downwardly independently of the depressor. Formed in body 10 is a cylindrical key receiving recess 28 and a pin 29, fixed in a side wall of the body, extends centrally of this recess and is adapted to be received in a cylindrical hole formed in the stem of a suitable key (not shown). Access to recess 28 is had by way of a key hole 30 formed in member 16. The pawl depressor 23 has a part extending into recess 28 and adapted to be engaged and moved by the bit of the key to retract pawl 18.

As a desirable adjunct to this, or any other handcuff lock, means are provided to prevent access of dirt and the like through key hole 30 into the recess 28. Such means includes a disc 31, the hub 32 of which is slideable on pin 29. A spring 33 keeps disc 31 tightly pressed against member 16 to close key hole 30. The disc 31 is provided with a recess 34 to permit it to pass by and clear depressor 23. Adjacent recess 34, the disc is provided with prongs 35 which enter the passageway 36 (connecting recesses 19 and

28) and these prongs, by engagement with the upper and lower walls of this passageway, prevent rotation of the disc. The latter may carry a pin, such as 37, to enter a notch in the bit of the key and member 16 70 is recessed to receive this pin and allow disc 31 to lie in contiguous relation with the member. The key is pushed into key hole 30 and the disc 31 is forced inwardly beyond depressor 23. Thereafter, the key is turned 75 to actuate the depressor and afterwards, as the key is withdrawn, disc 31 is moved back against member 16.

The invention, according to its broader features, is independent of the particular 80 type and construction of the handcuff and the locking means and the foregoing description is intended to set forth, as an illustrative example, one of many suitable types of handcuffs in which the invention may be 85 embodied. While the locking arm, as described, is not completely revoluble and the invention is most useful in connection with a locking arm thus arranged, nevertheless the invention is equally capable of use in a 90 handcuff wherein the locking arm is completely revoluble.

According to the more important features of the invention, the locking arm 12 is so arranged that it may at one position, (for 95 example that indicated by dotted lines in Fig. 1) be freed from the locking means, without resort to the key, and moved to open position in a direction opposite to that in which it was originally moved into locked 100 and wrist embracing position. To this end, the locking arm is preferably jointed or otherwise so constructed as to permit it to be moved bodily away from the locking means or substantially radially. In order 105 that the jointing of the arm may not be taken advantage of at undesired times, the arm and the frame of the handcuff are provided with interengaging means to prevent radial or approximately radial movement of 110 the arm except when the latter is moved inwardly toward the arms 11 beyond a predetermined point, at which the embrasure afforded by the cooperating arms 11 and 12 is too small to receive any ordinary wrist. 115

The interengaging means, referred to, may consist of a flange 38 on the locking arm which rides in under an overlying abutment 39, projecting inwardly from body 10, as 120 shown in Fig. 6. Any other suitable means may, however, be provided for this purpose. By reference to Fig. 1, it will be seen that the locking arm, at all positions in which it is engaged by pawl 18, is held by abutment 39 from moving away from the pawl in substantially radial directions. It is, however, within the province of the invention to provide for the release of the locking arm at an earlier position and while still engaged with pawl 18. It is also to be noted that al- 125 130

though arm 12 may be moved in its circular path until it is disengaged from pawl 18, it is not free from the pawl in the sense that it can be moved to open position. Arm 12 is not free for reverse movement, nor is it free for forward movement and but for its jointed connection it could not be released except by the use of the key operated means for retracting the pawl.

10 The arm 12 is connected to arms 11 by means of a short link 40 which is pivoted at one end at 41 to arm 12. This link is received in the forked end of arm 12 and can move relatively thereto through a small angle. A stop 42 on the link limits the relative movement between arm 12 and link 40 in one direction by abutment with the bottom surface 43 of the fork. A spring pressed plunger 44 engages in a recess 45 in link 40 and normally holds stop 42 against abutment 43 and the action of this plunger is strong enough so that the link and arm do not move relatively to one another during the operation of moving the arm into engagement with pawl 20. The arm 12 when so moved, will depress pawl 18 rather than cause plunger 44 to yield. A second stop 46 is provided on link 40 to limit, by abutment with surface 43, the amount of yield of plunger 44. A stop 47 may be provided on the opposite end of link 40 to abut a shoulder 48 on member 14 and limit the degree of swinging movement of arm 12 in a counterclockwise direction (as viewed in Fig. 1).

35 in the same manner as the movement of the arm might be limited by the abutment of its free end with the lower end of member 14.

In operation, assuming the arm 12 to be in the locked position shown by full lines in Fig. 1, it is moved into the dotted line position there shown and, when thus positioned, flange 38 has moved from under abutment 39. The arm 12 is then grasped near its pivotal connection 41 and pulled upwardly, 45 the arm being permitted by stop 46 to move sufficiently to bring its teeth 21 above the abutment 39. The arm 12 may thus be moved in a clockwise direction to open position.

50 The invention has been disclosed herein, in an embodiment at present preferred, for illustrative purposes, but the scope of the invention is defined by the appended claims rather than by the foregoing description.

55 What I claim is:—

1. A handcuff, comprising, a frame having a body portion and a fixed arm outwardly extending therefrom, a locking arm adapted to cooperate with said fixed arm to form an embrasure for the wrist and having a toothed segmental portion movable in a curved path in close proximity to said body portion, a key retractible locking device mounted in said body portion to engage the teeth on said locking arm, means connecting said arms so

that the locking arm is free to swing in said curved path and to move bodily away from said locking device, and means for confining the segmental portion of the locking arm to movement in said curved path except when 70 it has been moved toward said fixed arm beyond normal wrist embracing position.

2. In a handcuff, a frame, key releasable locking means therein, a locking arm mounted on the frame and movable in one direction into engagement with the locking means, and means whereby said arm after having been engaged with said means and moved into a predetermined position may be moved in a direction approximately normal to the first named direction to free it from said means.

3. In a handcuff, a frame, key releasable locking means therein, a locking arm pivoted to the frame and adapted to be moved 85 in an arcuate path into engagement with said means, means whereby said arm may be moved relatively to the frame in an approximately radial direction with reference to said path, and means for restraining movement of the arm in the last named direction while the arm is in locked position except when the arm is moved to a predetermined position.

4. In a handcuff, a frame, key releasable 90 locking means therein, a locking arm mounted on the frame and adapted to move in one path into engagement with said means, means permitting relative movement between said locking means and arm in a direction 100 such as to cause their disengagement, and means for restraining such relative movement after engagement of said arm and locking means until the arm has been moved in said path to a predetermined position.

5. In a handcuff, a frame, a toothed locking arm pivoted thereto for swinging movement in a curved path, locking means in said frame including a member to successively engage the teeth of said arm as the latter swings in one direction in said curved path, means permitting the arm to be moved in another path and in such a direction and to such a degree as to disengage said teeth and member, and means for restraining the last named movement of said arm after it has once been engaged with the locking means until the arm has been moved in said curved path into a predetermined position.

6. In a handcuff, a rigid frame, a locking arm provided with teeth, a link pivotally connected to said arm and to said frame, locking means in the frame including a member engageable with said teeth, and interengaging devices on said frame and arm to prevent relative movement of said arm and link while the arm is engaged with said locking means.

7. In a handcuff, a rigid frame, a locking arm provided with teeth, a link pivotally 130

connected to said arm and to said frame, locking means in the frame including a member engageable with said teeth, and interengaging devices on said frame and arm to prevent relative movement of said arm and link except at certain positions of said arm.

8. In a handcuff, a frame, a locking arm provided with teeth, a link pivotally connecting said arm and frame, means acting on said arm and link and tending to restrain relative movement thereof, locking means in the frame including a member engageable with said teeth, and interengaging devices on said frame and arm to prevent relative movement of said arm and link after said arm and locking means have been engaged

and until said arm has been moved to a pre-determined position.

9. In a handcuff, a frame, locking means carried thereby, a link pivotally connected to said frame, a locking arm pivotally connected to said link, means for limiting the degree of relative movement between said link and arm, resilient means for resisting said relative movement, and interengaging devices on said frame and arm to hold the latter when in certain positions against disengagement from the locking means.

In testimony whereof I have affixed my signature.

JOHN J. MURPHY.
